UNITED STATES PATENT OFFICE.

EDWARD J. MEYER, OF LAKEWOOD, NEW JERSEY.

VAPORIZING APPARATUS.

Application filed October 6, 1922. Serial No. 592,905.

To all whom it may concern:

Be it known that I, EDWARD J. MEYER, a citizen of the United States, residing at Lakewood, in the county of Ocean and State of New Jersey, have invented new and useful Improvements in Vaporizing Apparatus, of which the following is a specification.

This invention relates to accessories for attachment for automobile engines and has for its object the provision of novel means for utilizing the steam which forms in the radiator and also the vapors which accumulate within the crank case and which are ordinarily wasted, by collecting such steam and vapor, preheating it and then leading the mixture thereof into the intake manifold of the engine.

An important and more specific object is the provision of a mixing device which is carried upon the exhaust manifold so as to be heated thereby, this mixing device having connected therewith tubes or pipes which lead to the radiator, the breather and the intake manifold, the various vapors and steam mixed within the device being sucked into the manifold by the vacuum produced by the piston action during running of the engine.

An additional object is the provision of a fuel system of this character which will be simple and inexpensive in manufacture, easy to install, efficient and durable in service and a general improvement in the art.

With the above and other objects and advantages in view the invention consists in the details of construction to be herein-after more fully described and claimed and illustrated in the accompanying drawings in which:

Figure 1 is a side elevation of an engine radiator and a portion of the dash showing the device in applied position,

Figure 2 is an enlarged longitudinal section taken through the mixing device and showing its mounting on the exhaust manifold,

Referring more particularly to the drawings the letter A designates the engine of an automobile, B represents the radiator and C the dash. The type of engine makes no difference as the device is equally applicable to all makes. The engine is here illustrated as having the usual intake manifold D and exhaust manifold E. The oil breather pipe is designated by the letter F.

In carrying out the present invention use is made of a mixing device which consists of a preferably glass bowl 10 having a cover 11 and provided in its bottom with a metallic base 12 terminating in a threaded extension 13 which is screwed into a tapped hole in the exhaust manifold. There is no communication whatever between the exhaust manifold and the interior of the bowl the sole purpose being that the exhaust gases passing through the manifold will serve to heat the bowl to a moderate degree. It should be stated that the base is preferably angular so as to facilitate engagement by a wrench for effecting the turning action when screwing the device into place. Suitable gaskets 14 are of course provided for making the joints between the base and bowl and the cover and bowl tight.

Rising from the center of the base 12 is an upstanding tube 15 which is formed with a plurality of openings 16 which establish communication between its bore and the interior of the bowl and the upper end of this tube extends through the cover 11 and is threaded. The numeral 17 designates a pipe or tube which is connected with the projecting upper end of the tube 15 by a suitable connection 18 and which has its other end connected with a cut off cock 19 which is screwed into a tapped hole in the intake manifold D.

The cover 11 carries two nipples 20 and 21 with which are connected, by means of 22 and 23, pipes or tubes 24 and 25 which lead respectively to the radiator neck and breather pipe cap.

For the purpose of effecting control of the cock 19, I provide a control rod 26 which is connected with the handle thereof as for instance by a universal joint 27 and which leads rearwardly with its free end passing through the dash C and provided with a handle 28 operating over an indicator dial, the position of the handle upon the dial indicating whether the cock is open or closed or the degree of opening thereof.

In the use of the device it will be seen that the suction produced in the engine and consequently through the intake manifold will cause suction to be created in the bowl 10 and the result will be that steam and water vapor will be drawn in from the radiator through the pipe 24 while various oil vapors accumulating within the crank case will be drawn through the pipe 25 into

the bowl. If any of this vaporized matter condenses upon reaching the bowl and drops down thereinto, it will, upon reaching the upper surface of the hot plug or base 12, be revaporized. The water vapor and oil vapors will of course mix together within the bowl and will be sucked out through the tube 15 and will be drawn into the intake manifold of the engine, this hot mixed vapor commingling with the vaporized gasoline flowing through the intake manifold from the carburetor and effectually breaking it up and making a much more highly combustible mixture.

16 While I have shown and described the preferred embodiment of the invention it is of course to be understood that I reserve the right to make such changes in the form, construction and arrangement of parts as 20 will not depart from the spirit of the invention or the scope of the subjoined claims.

Having thus described my invention I claim:

1. A mixing device of the character described comprising a bowl formed for mounting upon the exhaust manifold of an internal combustion engine, a tube connected with a water supply and leading into the top

of the bowl, a second tube leading into the top of the bowl and connected with the breather of the engine, a tube extending axially of the bowl, and a pipe connected with said tube and with the intake manifold of the engine, said tube being provided at the bottom of the bowl with a plurality of openings and being also formed with openings at the intermediate portion of the bowl.

2. A mixing device of the character described comprising a bowl formed for mounting upon the exhaust manifold of an internal combustion engine, a tube connected with a water supply and leading into the top of the bowl, a second tube leading into the top of the bowl and connected with the breather of the engine, a tube extending axially of the bowl, and a pipe connected with said tube and with the intake manifold of the engine, said tube being provided at the bottom of the bowl with a plurality of openings and being also formed with openings at the intermediate portion of the bowl, 45

50 said bowl being of transparent material whereby the contents may be seen.

In testimony whereof I affix my signature.

EDWARD J. MEYER.
